210,493

COMBINED PORTABLE RADIO AND PHONO- GRAPH OR SIMILAR ARTICLE

Robert Hegon, 88 Rue de la Jarry,
Vincennes 94, France

Filed Dec. 1, 1966, Ser. No. 4,926

Claims priority, application Switzerland June 1, 1966

Term of patent 14 years

(Cl. D56—4)

FIG. 1

FIG. 2

FIG. 3

FIG. 4

FIG. 5

FIG. 6

FIG. 7

FIG. 8

FIG. 1 is a side, top and front perspective view of a combined portable radio and phonograph or similar article, showing my new design in its carrying position with the loudspeaker-containing cover assembled;

FIG. 2 is an exploded top, front and side perspective view in position for phonograph playing with the loudspeaker-containing cover disassembled;

FIG. 3 is a rear elevational view assembled;

FIG. 4 is a front elevational view;

FIG. 5 is a side elevational view;

FIG. 6 is an opposite side elevational view;

FIG. 7 is a bottom plan view; and

FIG. 8 is a top plan view thereof.

I claim:

The ornamental design for a combined portable radio and phonograph or similar article, as shown and described.
